UNITED STATES PATENT OFFICE

ROBERT A. CURRIE, OF SYRACUSE, NEW YORK, ASSIGNOR TO R. E. DIETZ COMPANY, OF NEW YORK, N. Y.

TORCH OR LAMP

Application filed March 28, 1930. Serial No. 439,648.

This invention relates to lamps or torches, and more particularly to improvements in torches of the sort that are employed, for instance, for lights and as danger signals on construction jobs and for other out-of-door uses where they are exposed to the varying out door weather conditions, but which are not provided with chimneys, globes or the like means commonly employed in lamps and lanterns for protecting the flame.

One object of the invention is to provide a torch of this sort which will be efficient, reliable and economical in operation.

Other objects of the invention are to produce a torch which will give the maximum light with the minimum consumption of fuel under the various different outdoor weather conditions; which is provided with a burner which will remain cool in operation and will insure a proper mixture of air and gaseous fuel with a consequent improvement in combustion, a white flame, and economy in operation; which will give a substantially unobstructed or open flame during normal weather conditions, but nevertheless is adapted to prevent the flame from being extinguished by strong winds, rain or snow; which is adapted to afford an exposed and substantially unobstructed flame under normal conditions, but is provided with a shield which can be readily adjusted when necessary to protect the flame from rain; which is provided with a movable rain shield which can be readily positioned over the burner when desired to protect the flame from rain and moved away from its operative position to leave the flame exposed and unobstructed when it is not raining; which is provided with a rain shield carried by a movable support by which the rain shield can be placed either into or out of shielding position and which support also serves as a carrying handle or bail for the torch; which is provided with a combined carrying handle and rain shield support which is movable to and from operative position for carrying the torch and for supporting the rain shield in operative position over the burner.

Another object of the invention is to improve torches of the type mentioned, whereby

they will have the advantages and features of improvement hereinafter described and set forth in the claims.

The accompanying drawings illustrate two constructions exemplifying slightly different practical embodiments of my invention. In said drawings:

Fig. 1 is a side elevation, on a reduced scale, of the upper portion of a torch showing one construction of the rain shield, with the shield and the combined carrying handle and rain shield support in operative position.

Fig. 2 is a similar view thereof showing the handle swung down with the rain shield out of its shielding position over the burner.

Fig. 3 is a sectional elevation thereof on line 3—3, Fig. 1.

Fig. 4 is a sectional elevation thereof on line 4—4, Fig. 3.

Fig. 5 is a plan view thereof, partly in section, on line 5—5, Fig. 3.

Fig. 6 is a horizontal section thereof on line 6—6, Fig. 3.

Fig. 7 is a fragmentary side elevation showing a slightly modified form of rain shield.

Fig. 8 is a plan view of the rain shield shown in Fig. 7.

10 represents the body or oil receptacle of the torch and 11 represents the torch burner at the top of the torch body. The torch body may be of any suitable construction, for instance, it may be a spheroidal sheet metal receptacle with a weighted bottom adapted to normally maintain the torch in an upright position and to return it to upright position in case the torch is turned over or knocked out of such position.

The torch burner is provided with a wick passage through which the usual wick 12 extends with its upper end exposed at the upper end of the wick passage. In the constructions shown, the burner comprises a tubular shell or body 13 and a vertical wick tube 14 which is disposed centrally in the shell 13, the wick tube being secured in a central hole 15 in the bottom wall 16 of the shell and in a central hole in a disk 17 which is secured in the burner shell between the ends thereof and forms the top wall of the

- burner. The wick tube may be secured in the holes in the shell bottom 16 and disk 17 by expanding the ends of the wick tube at the outer sides of the bottom 16 and top disk 17 or otherwise, and the disk 17 is shown as provided with a down-turned peripheral flange 18 which fits tightly in the shell 13 against an internal shoulder 19 in the shell, which prevents displacement of the disk in the shell. The burner may be secured in the torch body in any suitable manner, as for instance, by screw-threading the lower end portion of the burner shell, whereby the burner is adapted to be screwed into a threaded opening 20 in the top of the torch body.
- 21 indicates a ring or sleeve which surrounds and is welded, or otherwise rigidly secured, exteriorly on the burner shell, and the lower end of which provides a shoulder 20 adapted to abut against the top face of the torch body to form a practically tight closure for the burner opening 20 in the top of the body, which opening also serves as the filling opening for the torch.
- 25 The outer end of the wick tube 14 preferably extends somewhat above the top face of the top wall 17 of the burner and the shell or body 13 of the burner extends above the burner top 17 and above the outer end of the wick which, in its normal position, protrudes slightly out of the upper end of the wick tube. The shell 13 thus forms an open-topped tubular guard which surrounds the upper end of the wick and wick tube and forms an open-ended combustion chamber in which the flame is protected from being extinguished or blown out by strong winds, while nevertheless the upper end of this combustion chamber is open and unobstructed so 40 that the flame burning in this chamber can extend out through the open top thereof so as to burn freely and give an open or exposed flame and produce the maximum illumination.
- 45 22 represents holes through the burner shell 13, there being preferably a plurality of these holes disposed around the shell in a horizontal row and spaced apart equidistantly with the bottoms of the holes located below the horizontal plane of the outer end of the wick tube 14, and with the holes preferably extending somewhat above said horizontal plane of the outer end of the wick tube. The holes 22 serve the dual function of air inlet openings and outlet or drain openings for rain or water which may enter the open upper end of the shell or wind guard. Since the upper end of the wick tube extends above the top face of the burner top, and above the lower edges of the holes 22, the rain or water can drain freely out of the holes 22 and will not accumulate on the burner top sufficiently to rise above the top of the burner tube and wet the upper end of the wick or extinguish the flame.

While the burner is preferably constructed as shown, of the separate shell, wick tube and top disk 17, which can be conveniently made from tubes or sheet metal stampings, nevertheless it will be readily understood that a burner having similar form and characteristics could be made of other construction and could, if desired, be made of a single, integral casting or piece.

23 represents a rain shield which is mounted on the torch so that it is adapted to be supported in a position above or over the burner and spaced from the open, upper end of the burner shell 13, or to be moved to one side or away from this position over the burner. Preferably this rain shield is carried by a combined shield support and carrying handle 24 for the torch. As shown, the support or handle 24 is in the form of a U-shaped bail, the inner ends of the two legs 55 of which are bent inwardly at 25 and 26 and extend loosely through radial holes in the burner body, thus pivotally connecting the bail 24 to the burner. One of the pivots, 26, of the bail is preferably long enough to project through a hole in the side of the wick tube and engage or penetrate somewhat the side of the wick and thus serves as a wick retainer for holding the wick in adjusted positions in the wick tube and preventing the accidental displacement of the wick from the burner.

The rain shield 23 in the construction shown in Figs. 1-5 consists of a circular disk which extends horizontally between the legs of the bail 24, is preferably of slightly dome shape having a central opening 27, and is mounted on the bail by means of a slide or cross piece 28 on which the disk is rigidly secured by welding or otherwise, and which is provided at its ends with loops or guides 29 slidably engaging the legs of the bail 24 so that the cross piece with the rain shield can slide freely up and down on the bail. The cross piece 28 may be made of a piece of sheet metal which is suitably shaped by stamping or otherwise, to provide the guides or loops 29 at its ends, and preferably the central portion of the cross piece 28 is disposed beneath the central opening 27 of the rain shield disk and spaced downwardly away from the central portion of the disk. Thus, the cross piece 28 forms a baffle below the opening 27 of the rain shield, which prevents rain that might enter the opening 27 from falling on the wick and extinguishing the flame, while nevertheless the baffle 28 does not close the opening 27 in the rain shield, but permits the flame from the wick to issue and burn through the opening 27 and be seen above the rain shield.

Preferably the legs of the bail 24 are provided with lugs or projections 30 on which the rain shield guides 29 are adapted to rest, whereby when the bail 24 is in its upright po-

sition, the rain shield is supported off of and spaced from the upper end of the burner or wind guard. These lugs 30 support the rain shield at such an elevation above the upper end of the burner shell that when the bail is swung to and from its upright position, the rain shield will be prevented from striking the upper end of the shell so that the rain shield can be readily moved into and out of its shielding position simply by swinging the bail and without the necessity of shifting the shield on the bail to clear the burner shell. When it is not raining and the rain shield is not needed, the bail is swung down to one side out of its vertical position, and the rain shield is adapted to slide outwardly on the bail to a position at one side of the torch, as shown in Fig. 2. When it is desired to use the rain shield, it is simply necessary to swing the bail to its upright position and the rain shield can slide downwardly thereon until it rests on the lugs or stops 30, and is thereby supported above the burner.

The bail or rain shield support 24 can be releasably retained in its upright position by any suitable means, such as notches 31 (Figs. 2 and 5) in the opposite sides of the out-turned top flange 32 of the burner shell 13, into which notches the legs of the bail are adapted to spring or snap when the bail is in the upright position. The bail is preferably made of spring wire with a normal tendency for the legs to spring inwardly into holding engagement with the notches.

In the construction illustrated in Figs. 7 and 8, the rain shield is mounted on the burner in the manner described, but instead of the disk which forms the rain shield having the central opening, the shield is formed by a disk 23a having a plurality of circumferential slits and having the portions 33 of the disk opposite the slits pressed upwardly so that the slits form a plurality of flame openings 34 in the disk disposed preferably equidistant about the center of the disk. As in the case of the rain shield first described, the cross piece 28 is preferably spaced downwardly from the underside of the disk so that it will permit the flame to issue and burn through the openings 34 in the rain shield and will act as a baffle to prevent rain which may enter through these openings from falling on the wick and extinguishing the flame.

The burner is shown as provided at one side thereof with a lug or cam 35 which is so disposed that if the bail is swung down from its upright position towards the cam 35, the leg of the bail having the long pivot 26 will engage the cam 35 which will force the lower end of this leg outwardly and withdraw the pivot 26 from engagement with the wick, thereby freeing the wick and permitting the same to be adjusted in the wick tube. This cam, which may be conveniently formed by an outbent lug on the ring 21 of the burner,

thus serves as a means for releasing the wick-retaining pivot from holding engagement with the wick when it is desired to insert, remove or adjust the wick.

In the use of torches constructed as herein described, when it is not necessary to shield the wick from rain, the rain shield is left in its inoperative position shown in Fig. 2 at one side of the torch away from the burner. The flame will then issue unobstructedly through the open top of the burner shell and give the maximum light. The upper portion of the tubular burner body or shell 13, however, acts as a guard which prevents the flame from being extinguished by strong winds. Since the upper end of the combustion chamber formed by the burner shell or wind guard is open and unobstructed by a top, the burner will operate as an open or exposed flame burner and will keep cooler, with the result that it will produce a whiter and therefore more brilliant light, and will consume less oil than a burner in which the flame is confined or obstructed and acts to heat the burner more.

The reason for this, it is believed, is that with the open flame the burner operates under more natural conditions, and there is a more perfect mixture with a consequent improvement in combustion. The cooler the burner remains, the whiter will be the flame and the lower the consumption of oil. When it is necessary to shield the torch from the rain, the rain shield is moved to its position over the burner. The flame will then extend or burn through the opening or openings in the rain shield. Rain can enter through these openings, but the baffle 28 between the openings and the top of the wick prevents the rain from falling on and extinguishing the flame. The rain will be either dissipated by the heat of the baffle or it will be spattered to the sides and run off through the drain holes in the side wall of the burner body.

I claim:

1. A torch comprising a fuel receptacle having a passage for a wick, a wind guard which surrounds the outer end of said wick passage and is open at its outer end for the egress of the flame, and a rain shield which is supported above and spaced from the open outer end of said wind guard, said rain shield having an opening therethrough for the egress of the flame, and a baffle arranged relatively to said opening in the shield to protect the wick from rain.

2. A torch comprising a fuel receptacle, a burner thereon comprising a tube through which the fuel passes to feed the flame, and a tubular shell surrounding and projecting outwardly beyond the outer end of said tube, said shell having an open outer end for the egress of the flame, a wall connecting said tube and shell below the outer end of the tube, and said shell having one or more holes there-

- through disposed to permit liquid to drain off of said wall through said holes and prevent the liquid from accumulating on said wall to the level of the outer end of said tube.
3. A torch comprising a fuel receptacle, and a burner therefor comprising an upright tubular shell which is open at its upper end for the egress of the flame, a wick tube arranged within and spaced from said shell and terminating at its outer end below the upper end of said tubular shell, and a burner top extending from the outer end portion of said wick tube to said tubular shell, said tubular shell having holes therethrough disposed in a horizontal row around said burner and communicating with the chamber in said shell above said burner top.
4. A torch comprising a fuel receptacle, and a burner therefor comprising an upright tubular shell having an open upper end for the egress of the flame, a wick tube arranged within said tubular shell and terminating below the outer end of said shell, and bottom and top walls connecting said shell and said wick tube respectively at the lower and upper end portions of said wick tube, said tubular shell having holes therethrough arranged in a horizontal row and communicating with the chamber in said shell above said top wall.
5. A torch comprising a fuel receptacle having a passage through which the fuel passes to feed the flame, a rain shield, and a support for the rain shield movably mounted on the torch so as to move to carry said rain shield into and away from an operative position over the outer end of said fuel passage.
6. A torch comprising a fuel receptacle having a passage through which the fuel passes to feed the flame, a wind guard which surrounds the outer end of said fuel passage and projects outwardly beyond the same and has an open outer end for the egress of the flame, and a rain shield which is movably supported on the torch to move into and away from an operative position over said fuel passage and spaced from the outer end of said wind guard.
7. A torch comprising a fuel receptacle having a passage through which the fuel passes to feed the flame, a carrying handle for said torch, and a rain shield which is supported by said handle above the outer end of said fuel passage.
8. A torch comprising a fuel receptacle having a passage through which the fuel passes to feed the flame, a carrying handle for said torch, and a rain shield which is supported by said handle above the outer end of said fuel passage, said torch handle being movable to carry said rain shield to and from its operative position over said fuel passage.
9. A torch comprising a fuel receptacle having a passage for a wick, a rain shield, a support by which said rain shield is mov-
- ably mounted on the torch and supported over the outer end of said wick passage and which is movable to carry said rain shield to and from its position over the wick passage, said rain shield being movable on said support toward and from said wick passage.
10. A torch comprising a fuel receptacle having a wick passage, a rain shield, and a support for said rain shield which is adapted to stand in an upright position and support said rain shield over said wick passage and is movable out of said upright position to carry said rain shield to an inoperative position at one side of said wick passage, and means for releasably retaining said support in its upright position.
11. A torch comprising a fuel receptacle having a wick passage, a rain shield, and a support for said rain shield which is adapted to stand in an upright position and support said rain shield over said wick passage and is movable out of said upright position to carry said rain shield to an inoperative position at one side of said wick passage, and a retaining device which is engaged by said support in the upright position of said support for releasably retaining said support in upright position.
12. A torch comprising a fuel receptacle having a wick passage, a support which is movable to and from an upright position, a rain shield carried by said support and held thereby over said wick passage when said support is in the upright position, said rain shield being movable on said support toward and from said wick passage, and a stop which limits the movement of said rain shield on said support toward said wick passage.
13. A torch comprising a fuel receptacle having a passage through which the fuel passes to feed the flame, a carrying bail for said torch pivoted thereto to swing to and from an upright operative position, a rain shield carried by said pivoted bail and adapted to be supported by said bail over said fuel passage, said rain shield having guides slidably engaging the legs of said bail whereby said rain shield is movable on said bail toward and from said fuel passage.
14. A torch comprising a fuel receptacle, a burner therefor, a combustion chamber which surrounds the outer end of said burner and is open at its outer end for the egress of the flame, and a rain shield which is supported above said combustion chamber and spaced from the open outer end thereof, said rain shield having an opening for the egress of the burner flame, and a baffle spaced from said opening in the rain shield and between the same and said burner.

ROBERT A. CURRIE.
